UNITED STATES PATENT OFFICE.

ROMAN S. KWASIGROCH, OF CUDAHY, WISCONSIN.

LONGÉRON AND STATION BRACE FOR AEROPLANE FUSELAGES.

Continuation of application Serial No. 25,932, filed April 25, 1925. This application filed June 29, 1925.
Serial No. 40,293.

To all whom it may concern:

Be it known that I, ROMAN S. KWASIGROCH, a citizen of the United States, residing at Cudahy, in the county of Milwaukee and State of Wisconsin, have invented certain new and useful Improvements in a Longéron and Station Brace for Aeroplane Fuselages, of which the following is a specification.

10 The present invention relates to improvements in the braces used for connecting the stations to the longérons of an aeroplane fuselage, and has for its prime object to provide a structure wherein the longérons may 15 be constructed in a plurality of sections held together in my improved braces by a pressure wire. This assemblage enables injured parts to be easily and quickly replaced, in comparison to the ordinary construction 20 where the longérons are made in one piece.

Another important object of the invention resides in the provision of a brace provided with a plurality of receptacles, each independent of the others for receiving the ends 25 of stations and longérons and providing means for receiving the guy wires and one of said means being provided with an opening for receiving the pressure wire which holds the sections of the longérons together, 30 or assembled in the braces.

Another very important object of the invention is to provide a station and longéron brace of this nature which is exceedingly simple, strong, durable, reliable, and efficient in construction, and one which may be manufactured at a relatively low cost and is otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

This application is a continuation of my earlier application bearing Serial No. 25,932 and filed April 25, 1925.

In the drawing:—

50 Figure 1 is a detail view showing a part of a fuselage structure with a pair of my improved braces associated with stations and longéron sections and a pressure wire, and

55 Figure 2 is another view thereof, taken angularly to that shown in Figure 1.

Referring to the drawing in detail, it will be seen that the numeral 5 designates generally my improved brace which is provided with longitudinally extending receptacles 6 separated by a partition 7, and transversely extending receptacles 8 which are rectangularly disposed to each other and also rectangularly disposed to the receptacles 6. Apertured fins 9 are disposed in the usual manner between the receptacles 6 and 60 8, and an improved fin 10 is disposed between the adjacent sides of receptacles 8. My improved fin 10 is provided with a guy wire receiving aperture 11 and with an opening 12 adjacent the corner formed by the receptacles 8.

As stated in the objects of the invention, the longéron is formed in sections 13, the ends of which are receivable in the receptacles 6. The two ends in the receptacle 6 of 70 the same brace abut the partition 7, and are held in abutment therewith by a suitable pressure wire 14 which is engaged with the ends of the longérons in any suitable manner, not shown, and tends to draw the sections of the longérons together in end to end abutments, but since the ends of the longéron sections are separated by the partition 7, said ends are drawn into abutment with these partitions 7. The stations 15 are receivable in the receptacles 8 in the usual manner. The guy wires are attached in the usual manner by suitable fastening devices engageable in the apertures of the fins 9 and 10. 80 85

From the above detailed description it will be seen that should a longéron become broken, the broken sections thereof may be easily removed by releasing the pressure wire 14. It will also be seen that a broken 90 station 15 may be quickly and easily replaced should it become necessary.

In actual practice I find it desirable to construct the braces of steel, and the stations and longéron sections of duralumin, 100 wood, or some other suitable light tubing or solid rods in straight short lengths. The regular system of cross wires is used.

It is thought that the construction, utility, manipulation, and advantages of this invention should now be clearly understood by those skilled in the art of aeronautics.

The present embodiment of the invention has been disclosed merely by way of example to bring out clearly the utility and ad- 110

vantages of the invention since it attains in actual practice the various features of advantage enumerated as desirable in the statement of the invention and the above 5 description.

It is apparent, however, that numerous changes in the details of construction, in the sizes, in the materials, and in the combination and arrangement of parts may be resorted to without departing from the spirit or scope of the invention as hereinafter 10 claimed or sacrificing any of its advantages.

Having thus described the invention, what

I claim as new and desire to secure by Letters Patent is:—

A device of the class described including a body having longitudinally aligned receptacles for receiving longéron sections, and separated by a partition, and a station receiving receptacle rectangularly disposed to the longéron section receptacles, fins connecting the receptacles and provided with apertures, one of said fins provided with an opening for receiving a pressure wire. 20 25

In testimony whereof I affix my signature.

ROMAN S. KWASIGROCH.
